UNITED STATES PATENT OFFICE.

HERBERT A. CARHART, OF SYRACUSE, NEW YORK, ASSIGNOR TO ALEXANDER T. BROWN,
OF SYRACUSE, NEW YORK.

TYPE-WRITING MACHINE.

No. 884,638.

Specification of Letters Patent.

Patented April 14, 1908.

Application filed August 29, 1907. Serial No. 390,601.

To all whom it may concern:

Be it known that I, HERBERT A. CARHART, citizen of the United States, and resident of Syracuse, in the county of Onondaga and State of New York, have invented certain new and useful Improvements in Type-Writing Machines, of which the following is a specification.

My invention relates to typewriting machines and especially to a type bar and hanger construction for such machines.

One of the objects of my invention is to provide an improved ball bearing type bar pivot; another object is to provide a novel construction of type bar hanger having two type bars pivoted thereto, one on each side of the hanger; another object is to make provision for an arrangement of type bars whereby the room in the type bar segment is economized to the best advantage.

To these and other ends which will herein-after appear, my invention consists in certain features of construction, and combinations and arrangement of parts all of which will be fully set forth herein, and particularly pointed out in the claims.

In the accompanying drawings:—Figure 1 is a side elevation showing two type bars and the means for actuating the same, parts of a front strike typewriting machine being diagrammatically shown, some of them in section. Fig. 2 is a side view of two type bars mounted on a single hanger and off-set with relation to each other. Fig. 3 is a developed plan view of the right-hand half of a front strike type bar system constructed in accordance with my invention, parts being shown in section.

My invention is applicable to typewriting machines generally, but I have here shown it applied to a front strike typewriter. Said typewriter comprises a platen 10, a type bar segment 11, a sub-lever segment 12, and printing key levers 13, which last are pivoted at their rear ends on a cross bar 14.

The type bar segment 11 supports a series of type bar hangers each of which comprises a plate-like stem 15 which extends through and is seated in a suitable slot in the segment 11, and secured therein by a headed screw 16 threaded into the segment by the side of the hanger stem and having its head bearing on the upper edge of said stem; the hangers may, however, be secured to the segment in any other suitable manner. The forward end of

each of the hangers is formed or provided on each of its sides or faces with a boss circular in outline and having a conical periphery 17 which forms part of the stationary element of the ball bearing of a type bar, said boss 17 being preferably made an integral part of the hanger. The other part of the stationary element of the ball bearing consists of a plate 18 secured to the face of the associated circular boss on the hanger by a headed screw 19, the head of said screw being preferably counter-sunk into the plate as shown, so as not to project beyond the plate and thus unnecessarily to widen or thicken the bearing. Pins 20 passing through the plates 18 and into suitable openings in the faces of the circular bosses on the hangers, prevent the plates from turning on the screws 19. Each plate 18 has a conical periphery 21, which in conjunction with the conical periphery 17 of the boss of the hanger forms a circular race-way which is V-grooved in cross section for anti-friction balls 22, and each of the type bars 23 has at its pivotal end a circular ring or eye 24 which has an internal substantially V-shaped groove or ball race and constitutes the movable member of the ball bearing.

It will of course be understood that the bearing may be adjusted by tightening or loosening the screw 19. It will also be understood that as far as some features of my invention are concerned the details of the bearing may be varied and other means of adjustment provided.

The ball bearing just described is duplicated on the other side of the hanger so that two type bars are mounted on each hanger, the two type bars being separated only by the thickness of the plate-like stem 15 of the hanger. As these two type bars swing not in parallel planes but in planes which converge at the printing point, the two faces of the hanger and the conical peripheries 17 of the two bosses are not parallel but are suitably inclined with relation to each other.

Each circular series of balls 22 is situated in the median plane of the associated type bar and in the plane of its movement and is made of a diameter sufficient to steady the type bar in its swinging motion toward the printing point so that there is no tendency to lateral deflection of the type bar due to centrifugal force.

The typewriting machine, shown in the drawings, is a shift machine and each of the

type bars carries a type block 25 having two types 26 and 27, the platen being shiftable to cause one or the other of these types to print, as indicated diagrammatically in Fig. 1. In 5 a front strike machine of this class those type bars near the ends of the segment have their type blocks disposed transversely of the type bars at different angles as indicated in Fig. 3, and in order to economize the room in the 10 segment and to prevent the type blocks of adjacent type bars from interfering with each other, I mount those type bars that are near either end of the segment in a skewed arc, said type bars being mounted progressively nearer to the back of the machine as 15 the end of the segment is approached.

In Fig. 3 I have shown sixteen type bars on the right-hand half of the segment 11, said type bars being mounted on eight hangers. 20 The five hangers nearest the middle of the segment are at the same distance from the front of the machine, but the three hangers nearest the end of the segment are progressively stepped toward the rear of the machine, the segment itself being bent toward 25 the rear near its end as indicated in Fig. 3. In order that the progressive stepping of the type bars toward the rear may be regular these three end hangers are constructed differently from those hangers near the middle 30 of the machine. In the middle hangers the two bearings on each hanger are directly opposite to each other or are in alinement, whereas in each of the end hangers the bearings 35 are off-set or out of alinement, the one nearer the end of the segment being also nearer the rear of the machine. Moreover this off-set is different in extent in the different hangers, the hanger at the extreme end 40 of the segment having its two bearings off-set to a greater extent than the others; this being done on account of the fact that the type blocks 25 of the type bars mounted on this hanger stand more nearly at right angles to 45 the type bars than is the case with those type bars on the other hangers. The hanger and type bars shown in Fig. 2 are the ones at the extreme end of the segment as shown in Fig. 3, and in said figures the extent of off-set is 50 indicated by the lines *a* and *b* which pass through the respective centers of the two bars.

As far as some of the features of my invention are concerned any suitable means for actuating the type bars may be provided. As 55 shown in the present instance, each of said type bars is provided at the heel thereof with a lug or arm 28 to which is pivoted the rear end of a link 29 which lies beneath the type bar and which at its forward end is connected with the upstanding arm of a bell crank sub-lever 30 having a forwardly extending arm which is connected with a key lever 13 by a vertically disposed link 31. Each of the sub-levers 30 is pivoted at 32 in a hanger 33 pro-

jecting from the front face of the segment 12, to which it is secured by a screw 34. The links 29 pass through suitable openings in said segment 12, the upper edge of which has mounted thereon a pad or type rest 35 on which the forward ends of the type bars normally lie.

Various changes may be made in the details of construction and arrangement without departing from my invention.

What I claim as new and desire to secure by Letters Patent is:—

1. In a typewriting machine, the combination of a type bar hanger and two type bars one pivoted on each side of said hanger, the pivot for one type bar being off-set with relation to the pivot of the other type bar.

2. In a typewriting machine, the combination of a type bar hanger having on each side thereof a boss which constitutes one part of a ball bearing, and two type bars, one pivoted to each side of said hanger by said ball bearing, the pivotal center of one of said bearings being off-set with relation to that of the other.

3. In a front strike typewriting machine, the combination of a type bar segment, a series of type bar hangers mounted on said segment, and a series of type bars pivoted to said hangers, the type bars near the ends of the segment being pivoted progressively nearer to the rear of the machine, each of said hangers having a plurality of type bars pivoted thereto, and each of the hangers near the ends of the segment having the type bars pivoted thereto at different distances from the rear of the machine.

4. In a front strike typewriting machine, the combination of a series of front strike pivoted type bars, a segment in front of the pivots of said type bars and having a type rest on its upper edge, sub-levers pivoted to the front of said segment, links connecting said sub-levers with said type bars and passing through said segment, and keys for actuating said sub-levers.

5. In a typewriting machine, the combination of a series of segmentally arranged type bars, a series of individual hangers, a plurality of type bars being mounted on each hanger, the construction and arrangement of the parts and the connection of type bars to the hangers being such that the types are arranged in a skewed arc when in normal position.

6. In a typewriting machine, the combination of a series of segmentally arranged type bars, a series of individual hangers, a plurality of type bars being mounted on each hanger, the connection of the type bars to the hangers being such that the pivots of the type bars are arranged in a skewed arc.

7. In a typewriting machine, the combination of a series of segmentally arranged type bars, a series of individual hangers to which

said type bars are pivoted by ball bearings, a plurality of type bars being mounted on each hanger, the construction and arrangement of the parts and the connection of the type bars to the hangers being such that the types are arranged in a skewed arc when in normal position.

8. In a typewriting machine, the combination of a series of segmentally arranged type bars, a series of individual hangers to which said type bars are pivoted by ball bearings, a plurality of type bars being mounted on each hanger, the connection of the type bars to the hangers being such that the pivots of the type bars are arranged in a skewed arc.

9. In a front strike typewriting machine,

the combination of a type bar segment, a series of type bar hangers mounted on said segment, and a series of type bars pivoted 20 to said hangers, each of said hangers having a plurality of type bars pivoted thereto, and the hangers near the ends of the segment having the type bars pivoted thereto off-set progressively, whereby the pivots are ar- 25 ranged in an arc that is not circular.

Signed at Syracuse, in the county of Onondaga and State of New York this 22 day of Aug. A. D. 1907.
